UNITED STATES PATENT OFFICE.

ANDREW J. RAUERT, OF BUFFALO, NEW YORK.

DESIGN FOR A KEY-GUARD.

SPECIFICATION forming part of Design No. 34,687, dated June 25, 1901.

Application filed May 20, 1901. Serial No. 61,197. Term of patent 7 years.

To all whom it may concern:

Be it known that I, ANDREW J. RAUERT, a citizen of the United States, residing at Buffalo, in the county of Erie and State of New York, have invented and produced a new and original Design for a Key-Guard, of which the following is a specification, reference being had to the accompanying drawing, forming a part thereof.

This design relates to the shape or configuration of the key guards or fasteners which are employed for preventing unauthorized persons from turning a key from the outside of a door.

The accompanying drawing is a face view of a key-guard embodying my design.

As shown in the drawing, the leading or material features of my design consist of a pair of separated legs or members A, which are substantially parallel from their upper

ends nearly to their lower ends and which have their lower ends curved outwardly, as shown at a, an approximately heart-shaped loop B, located centrally at the upper end of the key-guard and having branches b, which extend outwardly from the base of the loop to the upper ends of the legs A, and eyes C, located at the junction of said legs and the branches b.

A minor feature of my design consists in the unequal length of the legs A.

What I claim is—

The design for a key-guard, substantially as herein shown and described.

Witness my hand this 18th day of May, 35 1901.

ANDREW J. RAUERT.

Witnesses:

THEO. L. POPP,

CARL F. GEYER.
